[57] CLAIM

The ornamental design of a rotatable boat hatch cover as shown and described.

DESCRIPTION

FIG. 1 is a top perspective view of a rotatable boat hatch cover showing my new design with cover closed;

FIG. 2 is a top perspective view of the rotatable boat hatch cover with the cover lifted;

FIG. 3 is a front perspective view of the lifted rotatable boat hatch cover;

FIG. 4 is a side elevational view of the lifted rotatable boat hatch cover;

FIG. 5 is a rear elevational view of the lifted rotatable boat hatch cover;

FIG. 6 is a front elevational view of a rotatable boat hatch cover;

FIG. 7 is a front elevational view with the rotatable boat hatch cover closed; and,

FIG. 8 is a side elevational view of a rotatable boat hatch cover and an open cover and an illustration of its use upon a phantom boat showing.

FIG. 8

FIG.2
